Assistant Examiner — Holly M Rodriguez

(57) **CLAIM**

The ornamental design for a skin care device, as shown and described.

DESCRIPTION

FIG. 1 is a perspective view of a skin care device design showing my new design.

FIG. 2 is a front view of the skin care device.

FIG. 3 is a rear view of the skin care device.

FIG. 4 is a left side view of the skin care device.

FIG. 5 is a right side view of the skin care device.

FIG. 6 is a top view of the skin care device; and,

FIG. 7 is a bottom view of the skin care device.

Any shading is not a feature of the design but is utilized to illustrate the surface contours of the skin care device design in the drawings.

The broken lines depict portions of the skin care device that form no part of the claimed design.

1 Claim, 7 Drawing Sheets
